STAMP DISPENSING MACHINE

Joseph Di Domenico, 575 Mount Pleasant Ave.,
Providence, R.I. 02908

Filed July 17, 1967, Ser. No. 7,825

(Cl. D52—3)

The drawing figure is a perspective view of a stamp dispensing machine, showing my new design.

The essential features of the design reside in the full-line portions of the front of the machine.

I claim:

The ornamental design for a stamp dispensing machine, substantially as shown and described.
